UNITED STATES PATENT OFFICE.

EMIL G. SAUER, OF RICHMOND HILL, NEW YORK, ASSIGNOR TO BIGELOW HARTFORD CARPET COMPANY, A CORPORATION OF MASSACHUSETTS.

DESIGN FOR A RUG.

48,792.

Specification for Design.

Patented Mar. 28, 1916.

Application filed February 17, 1916. Serial No. 78,999. Term of patent 3½ years.

To all whom it may concern:

Be it known that I, EMIL G. SAUER, a citizen of the United States, residing in Richmond Hill, in the county of Queens and State of New York, have invented a new, original, and ornamental Design for a Rug of Carpet Sizes, of which the following is a specification, reference being had to the accompanying drawing, forming part thereof.

The drawing illustrates a portion of a rug showing my new design.

I claim:

The ornamental design for a rug, substantially as shown.

EMIL G. SAUER.

Witnesses:

JOHN W. EATON,

H. V. CAMPBELL.
